UNITED STATES PATENT OFFICE.

CHARLES F. WALDRON, OF BOSTON, MASSACHUSETTS.

DESIGN FOR A HARNESS-TRIMMING.

SPECIFICATION forming part of Design No. 13,559, dated January 30, 1883

Application filed November 25, 1882. Term of patent 7 years.

To all whom it may concern:

Be it known that I, CHARLES F. WALDRON, a citizen of the United States, residing at Boston, in the county of Suffolk and State of Massachusetts, have invented a new, useful, and original Design for Harness-Trimming; and I do hereby declare that the same is fully described in the following specification and illustrated in the accompanying drawings.

The peculiarity of appearance which characterizes harness-trimmings embodying my design is a regular and successive notching of the external surface, corners, or edges of such trimmings by short connected depressions or recesses. This feature is clearly represented in the drawings, in which a terret, water-hook, and buckle are shown as illustrations of the goods to which my design is applied, each being ornamented by the succession of notches referred to.

Figure 1 is a terret, shown in elevation and edge view; and Fig. 2 shows similar views of a water-hook, while Fig. 3 is a plan of a buckle.

In these illustrations the notches *a* are in connected series along the corners of the article, 25 partly in the side and partly in the edge of it.

Trimmings of this character will usually be of highly-polished metal, and frequently will be gold or silver plated. This design is in all such cases very effective, the notches breaking 30 up the customary stiffness and angularity of appearance, and forming a succession of bright reflecting points at regular intervals, in pleasing contrast to the styles heretofore in use.

I claim as my invention—

The design herein shown and described, consisting of harness-trimmings having the external surface, corners, or edges formed with a connected series of notches or depressions, substantially as set forth.

In testimony whereof I hereto affix my signature in presence of two witnesses.

CHARLES F. WALDRON.
